UNITED STATES PATENT OFFICE

JULES GLAENZER, OF NEW YORK, N. Y.

COMPACT

Application filed July 7, 1931. Serial No. 549,282.

This invention relates to improvements in compacts or vanity cases.

The primary object of this invention is the provision of a relatively simple, easily handled, and compact accessory for ladies' use, which embodies a container having a latch key movably associated in an improved relation with the container, and embodying improved means for receiving cosmetics, such as rouge, lip-paste and the like. Thus the owner will invariably have her key at hand, inasmuch as it is very infrequent that a lady will neglect to have her vanity case about her person.

A further and important object of the invention is the provision of a relatively simple and efficiently arranged compact adapted to cooperatively receive an important key, such as the owner's house key and cosmetic material such as rouge and lip-paste, the device readily lending itself to formation out of precious materials.

Other objects and advantages of this invention will be apparent during the course of the following detailed description.

In the accompanying drawing, forming a part of this specification, and wherein similar reference characters designate corresponding parts throughout the several views,

Figure 1 is a perspective view of the vanity compact showing an association of a key with the body thereof, and initially showing the compact closures opened for access to cosmetic material therein, such as rouge and lip-paste, and the like.

Figure 2 is a perspective view showing the compact closed and the key collapsed therein.

Figure 3 is a horizontal sectional view taken longitudinally through the key compartment of the compact and showing the key collapsed therein; the dotted lines showing the relation in which the key may be projected and extended from the case body. This view has been taken substantially on the line 3-3 of Figure 4.

Figure 4 is a vertical sectional view through the compact taken substantially on the line 4-4 of Figure 3.

In the drawing, wherein for the purpose of illustration is shown only a preferred

embodiment of the invention, the letter A may generally designate the improved compact, which may include a container B cooperatively receiving a key C therein.

The body B is preferably a casting. It is intended that the device shall be made of precious metal, such as gold. The said body includes upper and lower walls 10 and 11 respectively, each of which includes a substantially circular disc-shaped head portion 13 and a reduced shank 14. The said walls 10 and 11 are integrally connected in spaced relation at the free ends of their shanks by means of an integral end wall 15. At one entire side of the compact the said walls 10 and 11 are also connected by a wall 17 extending from the wall 15 along the entire side of said compact and around the head or disc portions 13 of said walls and terminating at a shoulder 19. The compartment or space 20 between the walls 10 and 11 is relatively shallow and open at the opposite side from the wall 17 for the entire distance from the end wall 15 to the shoulder 19; the latter being placed short of the longitudinal axis of the compact, as is shown in Figure 3 of the drawing. This space or pocket 20 collapsibly receives a key C therein.

The key C is of the usual type, including a preferably flat head portion 25 and the kerfed shank 26. The head 25 is centrally pivoted by an adjustable rivet construction centrally upon the disc portions 13 of the upper and lower walls 10 and 11. This rivet construction includes a headed rivet body 28 inserted through aligning openings in the disc portions 13 and the key head 25; the head of the rivet 28 being relatively shallow and abutting on the top of the disc portion 13 of the wall 10. The stem of the rivet 28 is internally threaded for detachably receiving a headed set screw 29 which is threaded thereinto from the lower side of the disc 13 of the wall 11, as shown in Figure 4, and these inter-threaded portions 28 and 29 may be adjusted to vary the frictional clamping of the head of the key C between the walls 10 and 11, so as to vary the frictional resistance imposed to the swinging of the shank of the key into or out of the pocket 100

20, as can readily be understood. It is contemplated to make the compact of very precious materials, and in that event the lower head of the screw 29 may be suitably recessed for receiving a precious stone. The shank 26 of the key of course collapses into the stem portion of the body B, that is, between the shank portions 14.

To facilitate the projection of the shank 26 out of the pocket 20 it is contemplated to provide an ejecting device 30, which consists of a slide bar body 31 at the inner side of the wall 15 within the pocket, paralleling the same. This slide bar 31 is provided with a headed handle 33, which extends through a horizontal slot 34 provided in the wall 15, so that the finger-nail or tip of the finger of a user may laterally slide the handle 33 back and forth, and correspondingly move the bar 31 therewith. The bar 31 within the pocket 20 is provided with a normal extension 35 which lies between the shank of the key and the wall 17; preferably adjacent the latter, so that movement of the ejecting device 30 from the position shown in Figure 3 will cause an ejection of the shank of the key from the full line position shown in Figure 3 to the adjacent dotted line position shown in said view, and from which it may be further moved to the full operating position, as also shown by dotted lines in Figure 3. In the latter position the key at the juncture of the shank portion and head portion thereof may abut against the shoulder 19 to permit the user to readily grasp the case body in his or her hand for the purpose of properly manipulating the key in a lock or latch.

The disc portion 13 of the wall 10 is provided with an annular upstanding wall 40 defining a pocket 41 which is counter recessed at 42 (see Figure 4) for the purpose of receiving a cake of rouge or similar cosmetic. This counter recessed portion 42 occupies substantially the lower half of the depth of the pocket 41, and in the upper portion of said pocket there is adapted to be received a puff or rouge applicator, if desired. The upper annular edge of said wall 40 is reduced at 45, best shown in Figure 1. At a point diametrically opposed from the shank portion of the body B the wall 40 has hinged therewith at 50, a disc-shaped cover 51 for the pocket 41, having an annular attaching flange 52 which is adapted to receive therein the reduced edge 45 of the wall 40 to frictionally close the pocket 41. This lid or closure 51 is preferably counter-recessed to receive a mirror 55 therein in any approved relation. It may be held in place by a split spring ring.

It is to be noted that the shanks or stem portions 14 of the plates 10 and 11 are of generally elongated rectangular shape. On the stem portion of the upper wall 10 there is

peripherally provided an upstanding wall structure defining a lip-paste receiving pocket 60. This upstanding wall structure comprises side walls 61 and 62 and an end wall 63 contiguous with and integral with the wall 15 above described. The walls 61 and 62 of course integrally merge with the annular wall 40 defining the rouge pocket 41 and at the juncture therewith there is provided a baffle wall separating the pockets 41 and 60. At this baffle wall there is provided a closure 65 hingedly pivoted at 66 upon the body, which is provided with a reduced retaining flange 67 adapted to frictionally fit into the pocket 60 in abutment with the inner surfaces at the tops of the walls 61 and 62 to frictionally hold the said closure shut. Both the closures 51 and 65 are provided with nail engaging extensions 70 at their free ends, to facilitate their lifting. It is to be noted that both closures 51 and 65 operate on parallel pivot axes, and when both of said closures are open access may be readily had to the materials therein without mutual interference.

A desirable feature of the invention is the provision upon the inside surface of the wall 63 of a scraping extension 75 which projects into the pocket 60 spaced above the bottom thereof and which may have an edge against which the owner may scrape her finger to remove residue lip-paste. It is of course the intention in providing the elongated pocket 60 that the user will rub her finger over the paste material in the pocket, starting at the end of the pocket adjacent the pivot of the closure 65, and moving the tip of her finger over the paste cake in the direction of her body. It will thus be understood that sufficient of the paste may be removed with facility for application. Any residue may be removed by scraping the tip of the finger against the bar 75.

In further embellishment of the device the ejector head 33 may have a precious stone set therein.

The use of the device will be apparent. It is a well known fact that ladies seldom forget to take along their compacts and vanity cases. However, it is quite frequently that they neglect to take along house keys. By cooperatively associating the house key with the compact the problem of "forgotten keys" will be solved to advantage. In using the device with both of the closures 51 and 65 open, the user may eject the shank of the key C and hold upon the same to steady the container. When using the mirror the key may be collapsed in its pocket and the closure 65 shut, and of course the shank end of the container may then be held in the hand of the user with the lid 51 tipped back for exposing the mirror.

It is intended that the device may be made of any material. In the main it will be made of precious metals, such as gold, and either

engraved or enameled. The key when collapsed in the pocket 20 is completely hidden except for the edge which is visible at the opening slot of the pocket 20.

5 Various changes in the shape, size, and arrangement of parts may be made to the form of invention herein shown and described, without departing from the spirit of the invention or the scope of the claims.

10 I claim:

1. In a device of the class described, an elongate flat key-shaped casing including a disc-shaped head portion and a shank extending radially therefrom, said casing having a cosmetic receiving compartment in the head and a cosmetic receiving compartment in the shank opening to one face of the casing, and a key-shaped compartment beneath said first and second mentioned compartments conforming substantially to the shape of the head portion and shank and opening at another portion of the casing.

2. In a compact the combination of a case body including a substantially circular disc-shaped receptacle head portion defining a pocket opening in a line normal thereto, a substantially radially extending shank portion rigidly connected with said disc-shaped head portion and having a pocket opening normal thereto and in the same direction as the pocket of said head portion, said pockets being adapted to receive cosmetic material, and said case body having a laterally opening pocket therein beneath the above mentioned pockets, of substantially the same shape as said case body head and shank.

3. In a compact the combination of a casing body having a pocket therein, a closure for the pocket, said pocket being adapted to receive lip-paste, and a scraper bar mounted in said pocket in position to permit the scraping of residue paste from the finger of an operator.

4. In a vanity compact the combination of a casing having a lip-paste receiving pocket of elongated shape, closure means operatively mounted at one end of said pocket, and a scraper bar in the pocket at the opposite end in position to permit the scraping of residue paste from the finger of an operator after passing along said pocket in the direction of said bar.

5. In a compact, the combination of a casing having a paste receiving pocket therein, and a scraper in the pocket in position to permit the scraping of residual paste from the finger of an operator.

6. In a compact, the combination of a casing having a paste receiving pocket therein, and a scraper carried by the casing in position to permit the scraping of residual paste from the finger of an operator.

JULES GLAENZER.
